Attorneys.

UNITED STATES PATENT OFFICE.

FRANK M. KIRKPATRICK, OF ADAMS, WISCONSIN, ASSIGNOR OF ONE-THIRD TO JOHN PETERSON AND ONE-THIRD TO CHARLES BOETCHER, BOTH OF ADAMS, WISCONSIN.

RAILWAY-SWITCH.

1,331,868.

Specification of Letters Patent. Patented Feb. 24, 1920.

Application filed November 12, 1919. Serial No. 337,431.

To all whom it may concern:

Be it known that I, FRANK M. KIRKPATRICK, a citizen of the United States, and resident of Adams, in the county of Adams 5 and State of Wisconsin, have invented new and useful Improvements in Railway-Switches, of which the following is a description, reference being had to the accompanying drawings, which are a part of this 10 specification.

The present invention relates to certain new and useful improvements in railway switch construction.

In the present switch constructions it is 15 quite often the case that after continuous use the switch point or tongue sometimes fails to have a snug engagement with the adjacent rail and therefore a car or engine wheel having a sharp flange will sometimes 20 open or cut between the switch point and rail and thus become derailed as the following wheel, the flange of which may not be sharp enough to cut between the switch point and the rail, will ride upon the switch 25 point. Such accidents are oftentimes disastrous, causing the loss of life and are also expensive to right.

Hence with the above and other inherent 30 objections in mind, my invention has for one of its objects to provide a railroad switch in which the switch point or tongue is adjustably connected with the operating bar by a universal joint or the like, whereby the same may be adjusted to at all times 35 have a tight or snug engagement with the adjacent rail.

Another object of my invention is to provide a novel form of means for resiliently retaining a switch point or tongue in engagement with the railway rail so that the 40 spring means may be maintained in oil or grease to prevent rusting and the consequent breakage due to rust.

A further object of the present invention 45 is to provide a railway switch construction which will be compact in structure efficient in operation and durable.

With the above and other objects in view 50 which will appear as the description proceeds, my invention resides in the novel construction, combination and arrangement of parts, substantially as hereinafter described and more particularly defined by the appended claims, it being understood that 55 such changes in the precise embodiment of

the herein disclosed invention may be made as come within the scope of the claims.

In the accompanying drawing I have illustrated one complete example of the physical embodiment of my invention constructed according to the best mode I have so far devised for the practical application 60 of the principles thereof, and in which:

Figure 1 is a top plan view of a railway switch embodying the features of my invention.

Fig. 2 is an enlarged fragmentary view, part in section and part in elevation and taken on the general plane indicated by the line 2-2 of Fig. 1, and

Fig. 3 is an enlarged sectional view of a switch point moving member, said view being taken on the line 3-3 of Fig. 1.

Referring now more particularly to the accompanying drawing, the numeral 5 designates the usual railroad rails, one of which is straight and the other of which branches diagonally therefrom as at 6, a switch point or tongue 7 being engageable with the rail 5 from which the section 6 75 branches off at the curve thereof to form a continuation of the track and a switch point or tongue 8 being engageable with the other rail 5 at a point adjacent the branching of the section 6 in order to provide the corresponding rail for the track formed by rail section 6.

As is usual in structures of this character, the switch points are connected together by means of a cross bar 9 so that the switch 90 points may be selectively engaged with the adjacent rail to direct a train to the track desired and I employ novel means for connecting the switch points with the cross bar 9 including a substantially U-shaped 95 bracket member 10 secured to the cross bar by fastening members 11 adjacent each switch point. A threaded rod 12 is adjustably engaged within alined threaded openings 13 formed in the arms 14 about each 100 bracket member, the outer end of the threaded rod having a bolt 15 formed thereon which is pivotally disposed within a socket 16 formed in a securing block or member 17 secured to the adjacent switch point.

The inner end of the rod 12 is squared as at 18 so that the relation of each frog with its bracket 10 may be adjusted to insure the proper engagement of the switch point with its adjacent rail and the rod is locked in its 110

adjusted position by means of lock nuts 19 engaging the opposite sides of one of the arms 14, see Fig. 2.

This structure besides providing an adjustable connection between the switch points and the cross bar, also provides a pivotal connection therebetween. The outer end of the cross bar 9 is reduced as at 20 and has secured thereto a coupling 21 forming a part of a universal or ball and socket connection between a rod section 22 of a two part resiliently connected operating rod to be later described. This universal joint connection includes a ball 23 formed on the outer end of the rod section 22 and secured within the coupling 21 by means of a threaded socket member 24 which is adjustable to take up any possible wear between the parts and is retained in its adjustable position by means of a set screw 25. In order that this joint may be properly lubricated an oil opening 26 is provided within the coupling 21 and in communication with the surface of the ball 23.

The rod section 22 is resiliently connected with an operating rod section 22' by means of a cylindrical casing 27 having its ends closed by centrally apertured cap members 28 and 29, the rod 22' having its inner end in threaded engagement with the aperture of the cap 29 and the rod 22 having its inner end slidably projected into the casing through the aperture of the cap 28. The inner end of the rod 22 has an enlargement or flange 30 formed thereon and against each face of which impinges an end of an extensile spring 31 having its other end impinging against the adjacent cap closing the ends of the casing. The springs 31 are under tension at all times and as they contact against each other the end 30 of the rod 32 will be normally urged to position centrally of the casing.

From this structure it will be seen that when the rod 22' is moved to the left with reference to the drawing, the spring being of equal tension will move the switch point 7 to engagement with its adjacent rail, as depicted in Fig. 1, in which case a train backing onto the main track from the spur or section 6 may wedge the switch points to the proper position to permit its passage on the main track without affecting the setting of the switch for a train coming in the opposite direction. In such an event the rod 22 will be moved against the action of the spring 31 disposed between the head 30 and the cap 28 which spring will return the switch point to its set position after the car wheels will have passed thereby. When the switch is set for a train passing along the straight track the action will substantially be reversed from that just described and further description thereof is thought unnecessary.

In order to protect the springs 31 from the elements the casing 27 is inclosed within a housing 32 fixed to the adjacent extended tier 33 by means of cradle arms or brackets 34, and the housing has its ends closed as at 35 through which the rods 22 and 22' project, a suitable packing gland or stuffing box 36 being formed in each end of the housing so that no moisture can pass into the housing where the rods project thereinto. If desired the housing may be filled with oil or grease placed therein through an oil opening 37 normally closed by a removable plug or cap 38 as shown in Fig. 3.

What I claim for my invention is:

1. A railway switch comprising a switch point, an operating bar, and a ball and socket joint adjustably connecting the switch point and operating bar.

2. A railway switch comprising a switch point, an operating bar, a socket member secured to the switch point, an adjustable rod carried by the operating bar, and a ball formed on one end of said rod and pivotally secured in said socket member.

3. A railway switch comprising a rail, a switch point movable to and from engagement with the rail, an operating bar, a socket member secured to the switch point, a bracket member secured to the operating bar, a threaded rod adjustably carried by the bracket member, and a ball formed on one end of said rod and pivotally secured in the socket member.

4. A railway switch including means for operating a switch point and comprising a fixed cylinder having alined apertures in its ends, a rod slidably projected into the housing through each aperture therein, a tubular member disposed within the housing and having the end of one of the rods secured thereto and the end of the other rod slidably mounted therein, and spring means normally urging the end of said other rod centrally of the tubular member.

5. A railway switch including means for operating a switch point and comprising a fixed cylinder having alined apertures in its ends, a rod slidably projected into the housing through each aperture therein, a tubular member disposed within the housing and having the end of one of the rods secured thereto and the end of the other rod slidably mounted therein, a packing gland at each end of the cylinder for preventing the entrance of moisture where the rods pass into the cylinder, and spring means normally urging the end of said other rod centrally of the tubular member.

6. In a railway switch, the combination with two rails and two switch points adapted to be selectively moved to and from engagement with the rails thereadjacent, of a cross bar, bracket members carried by the cross bar, adjustable rods carried by the

bracket members and in pivotal connection with the switch points, whereby the distance between the switch points may be readily adjusted, a casing, a control rod having one end fixed to the casing, a connecting rod having one end slidably mounted in the casing, an enlargement on said end of the connection rod, and an extensile spring impinging against each side of the enlargement and

the adjacent end of the casing whereby said 10
enlargement will be normally urged to a position substantially centrally of the casing, and an adjustable universal joint connection between the other end of said connecting rod and said cross bar.

15

In testimony whereof I affix my signature.

FRANK M. KIRKPATRICK.
